GAS FILLED TUBE

Carl J. R. H. von Wedel, Hilversum, Netherlands,
assignor to Electrons, Inc., a corporation of
Delaware

Application August 30, 1930. Serial No. 478,855

7 Claims. (Cl. 250—27.5)

This invention relates to gas filled tubes of the type adapted to carry relatively heavy currents, such as rectifiers, and has for its object means to prevent injury to such tubes by a rush of plate current at the time of starting the tubes.

The present construction of gas filled rectifiers, except in the case of very small tubes, requires closing the filament circuit and waiting for the filament to heat up before closing the plate circuit. The necessity for this delay is due to the fact that with tubes having more than approximately 50 volts on the plate, the gas becomes ionized as soon as the plate potential is applied and the direct current circuit closed. These ions falling through the full potential of the plate circuit acquire a high velocity and bombard the filament causing a rapid disintegration and sputtering of the latter. After the filament is heated up, however, it emits sufficient electrons to neutralize most of the ions before they reach the filament, and those which do fall on the filament have only a velocity corresponding to the potential drop across the arc which is relatively low, being of the order of 10 volts, and do not cause rapid disintegration of the filament.

Also, when currents of low amperage are used the bombardment during the starting period of the tube is fairly well distributed over the entire cathode or filament and the disintegration may be sufficiently slow to give the tube a practical life. But with currents of the order of an ampere or more the bombardment is apt to concentrate on one spot, heating it up so that it emits electrons with the result that the whole load is carried on one small hot spot or scintillation point, and the cathode and its oxide coating disintegrate rapidly at this point. The result is that the tube will only stand a very limited number of cold starts, and each start reduces the life considerably, so that such tubes are not practical commercially.

The delay in waiting for the filament to attain the proper temperature is inconvenient, and is not always observed, so that many manufacturers will not risk putting out apparatus in which the proper performance depends upon the operator waiting the requisite period of time before closing the plate current switch. The alternative is to use an expensive time relay the cost of which is often prohibitive and is many times the cost of the tube itself.

In my invention I overcome the above objections by providing an electric shield or screen to prevent bombardment of the filament during the starting period, which screen does not interfere

with the normal operation of the tube after the filament has reached the proper operating temperature.

Fig. 1 of the drawing is a side view partly in section of a tube constructed in accordance with my invention;

Fig. 2 is a section of the anode assembly taken along line 2—2 of Fig. 1; and

Fig. 3 is a view of my screen looking downward as indicated by line 3—3 of Fig. 1.

Referring to Fig. 1 a gas-filled tube adapted for full wave rectification and having an anode assembly comprising carbon plates 1 and 1', metallic anode shield 2 and supporting stem 3 is shown. Conductors 4 and 4' connect the respective plates 70 in circuit with a transformer winding 9 which serves as the source of supply. A mid-point connection, as shown, from winding 9 goes to one side of the direct current line, the other side of the line returning to the mid-point of winding 10 of 75 the filament supply transformer to complete the plate circuit. The shield 2 (a sectional view of which is shown by Fig. 2) is separated from the plates by a distance approximately equal to the mean free path of an electron in a tube of this 80 type and prevents short-circuiting action between the anodes in a full wave rectifier. This shield is also connected to member 6 by conductor 8 to maintain a proper potential thereon. Any other desired anode arrangement, however, may be used. 85

The oxide coated filament or cathode elements 5 shown in Figs. 1 and 3 may also be of any desired type altho I prefer to use the coil type and energize the same from the secondary 10 of an alternating current supply transformer. Surrounding the filaments is a cylindrical metallic shield member 6 which is maintained at approximately cathode potential by connecting the filaments thereto at their upper ends as shown. At the upper end of member 6 is a metallic shield 95 7 in the form of a wire mesh screen which is thus inserted between the filaments and plate. The electrostatic field and therefore the ionization of the gas exists largely between this shield and the plate, and the difference in potential and voltage gradient between the screen and the filaments will be very small.

During starting of the tube the shield acts as a cathode and receives all the bombardment and disintegration whereas the filaments are only 100 bombarded by a few stray ions falling through the screen. Practically all of the field is between the screen and plate and but very little ionization occurs within the member 6. After the filament is heated up, however, the ionization is 105 110

evenly distributed both within and without the shield 6 and the arc drop is approximately the same or perhaps slightly higher than that in a similar tube without the shield. During the starting period the screen 7 becomes quite luminous due to the bombardment but becomes relatively dark as soon as the filament has heated up.

The screen member 7 may be made of metal, such as nickel, which will not disintegrate as rapidly as the oxide coating of the filaments, and can also be made so that a considerable amount of disintegration of the screen can take place without interfering with the operation of the tube. After the filaments have reached the proper temperature the electrons emitted by them ionize the gas between the screen and the filaments, and the field exerted by the screen is almost completely neutralized by the ions on the surface of the screen, and the tube operates very much as if the screen were not present, the only difference being a slight constriction of the area of the arc discharge due to the space taken up by the screen and by the sheath of ions surrounding each wire. In some cases this may increase the arc drop in the tube a fraction of a volt or so.

The screen serves another important purpose, as follows: When the tube is operating and the load is suddenly increased, a transient condition of ionization is set up during which time the arc drop is considerably higher than normal. This condition lasts for several cycles before the filaments have readjusted themselves to the new temperature and emissive conditions necessary to restore the arc drop to its normal value. During this time the screen tends to maintain a more normal arc drop in the neighborhood of the filaments and takes the bombardment due to the higher arc drop from screen to plate. This shielding lengthens the life of the tube subjected to intermittent and rapidly fluctuating loads. The fact that it screens the filaments from bombardment reduces the tendency to sputter the coating during starting and transient conditions and thus reduces the tendency of arc-over in the tube.

The side and bottom of the shield 6 may be made of nickel or other suitable material, and the connection to the lower end of the filaments passed through an insulating tube 11, the upper end of the filaments being connected to the nickel member. Lead-in wires 12 connected in parallel to provide greater current carrying capacity are connected to the common terminal of filaments 5, while lead-in wires 13, also connected in multiple, serve to support the member 6 and provide a connection to complete the filament heating circuit. The tube may be connected to its external filament and plate circuits in various other ways than the conventional manner shown.

While the above construction embodies a preferred form of my invention, it is to be regarded as illustrative only since various additional uses and modifications thereof will readily suggest themselves to those skilled in the art without the exercise of inventive skill and without departing from the spirit and scope of my invention.

I claim:

1. In combination in a gas filled tube, an anode, a heatable emissive cathode, means comprising a shield enclosing said cathode and having a discharge opening of sufficient area to offer substantially no resistance to the discharge cur-

rent, and conductive means dividing said opening into numerous small openings and adapted to prevent destructive bombardment of the cathode during periods of relatively low cathode emission.

2. A low voltage arc tube having cathode and plate electrodes, an electron emissive coating on said cathode, a metallic shield interposed between said electrodes having a large opening for the main discharge path and a conductive mesh covering said opening, and means for maintaining said shield and mesh at approximately cathode potential, whereby said coating is protected from destructive ionic bombardment during periods when the cathode emission is inadequate for the discharge current. 80

3. A gas filled tube having a plate electrode and a filament with an emissive coating thereon, a cylindrical metallic shield within the tube and surrounding the filament, said shield being maintained at approximately filament potential and having its end which is adjacent the said plate electrode covered with metallic mesh to prevent ionic bombardment of the filament coating during starting of the tube and before the filament has 95 reached the proper emitting temperature, but permitting normal operation of the tube when the proper emissive condition of the filament obtains.

4. A gaseous rectifier tube having a plate electrode and a plurality of filaments with emissive coatings thereon, a cylindrical metallic shield within the tube and enclosing said filaments, one end of each filament being connected to the shield to maintain the same at approximately 105 filament potential, and a conductive mesh forming that part of said shield between the plate and filaments, to prevent ionic bombardment of the filament coatings before the filaments have 110 reached proper emitting temperature but permitting normal operation of the tube when the proper emissive condition of the filament obtains.

5. A cathode structure for a gaseous discharge tube comprising a heatable filament, an 115 electron emissive coating thereon, a metallic enclosure for said filament having a main discharge opening therein and a conductive mesh screen over said opening.

6. A gaseous discharge tube comprising a plurality of electron emissive filaments connected in parallel, a metallic enclosure for said filaments, a plurality of anodes external to said enclosure, said enclosure having an opening therein for a gaseous discharge between said filaments and 130 anodes, a substantially non-emissive metallic screen covering said opening, and a metallic shield separating said anodes, said screen, shield, enclosure and filaments being conductively connected within said tube. 135

7. A gas filled discharge tube having a heatable emissive cathode, an anode, a metallic screen member interposed between said electrodes and adjacent the cathode, means cooperating with said member for directing the main discharge current through the openings therein, and means for maintaining said member at approximately cathode potential, the said member preventing destructive ionic bombardment of the cathode surface during periods when the cathode is not 145 sufficiently emissive for the discharge current and offering substantially no resistance to the discharge when the cathode emission is normal.
